(57) **CLAIM**

The ornamental design for a back applicator, as shown and described.

DESCRIPTION

FIG. 1 is a perspective view of the back applicator of our new design;

FIG. 2 is a front view of the back applicator, as shown in FIG. 1;

FIG. 3 is a rear view of the back applicator, as shown in FIG. 1;

FIG. 4 is a left view of the back applicator, as shown in FIG. 1;

FIG. 5 is a right view of the back applicator, as shown in FIG. 1;

FIG. 6 is a top view of the back applicator, as shown in FIG. 1; and,

FIG. 7 is a bottom view of the back applicator, as shown in FIG. 1.

The dash-dash broken lines represent portions of the back applicator and form no part of the claimed design. The dash-dot-dash broken lines define the bounds of the claimed design and form no part thereof.
